UNITED STATES PATENT OFFICE.

TARGE G. MANDT, OF STOUGHTON, WISCONSIN.

DESIGN FOR A RUB-IRON.

SPECIFICATION forming part of Design No. 35,107, dated September 17, 1901.

Application filed August 10, 1901. Serial No. 71,662. Term of patent 7 years.

To all whom it may concern:

Be it known that I, TARGE G. MANDT, a citizen of the United States, residing at Stoughton, in the county of Dane and State of Wisconsin, have invented and produced a new and original Design for Rub-Irons, of which the following is a specification.

My invention relates to a new and useful design for chafing-plates or rub-irons for vehicles, of which the following is a specification, reference being had to the accompanying drawings, forming a part thereof, in which—

Figure 1 is a perspective of my rub-iron. Fig. 2 is a transverse section of the same. Fig. 3 is a plan view of the flange.

Like numerals of reference designate like parts in the different views of the drawings.

The numeral 1 designates the body portion of the rub-iron, which body is curved on the arc of a circle, forming a concave face 2. The body 1 is rounded off on the upper corners at 3 and has a flange 4 formed integral therewith and connected to the lower edge there-

of. The junction of the flange 4 and the body 1 is rounded off at 4^a. The flange 4 extends at right angles to the body 1 and is perforated at 5 and slotted at 6. The rear edge 4^b of the flange 4 is rounded off in the back on an arc concentric with the arc of the face.

The essential or material features of my design are the body 1, rounded off on the upper corners at 3 and having a concave outer face, and a perforated and slotted flange 4 extending at right angles to said body.

Having described my invention, what I claim as new, and wish to secure by Letters Patent, is—

The design for a rub-iron, substantially as shown and described.

In testimony whereof I have hereunto set my hand in presence of two subscribing witnesses.

TARGE G. MANDT.
